UNITED STATES PATENT OFFICE.

JOHN W. BROWN, OF COLUMBUS, OHIO, ASSIGNOR TO THE J. W. BROWN MANUFACTURING COMPANY, OF COLUMBUS, OHIO, A CORPORATION OF OHIO.

LAMP.

1,413,962.

Specification of Letters Patent. Patented Apr. 25, 1922.

Application filed November 18, 1920. Serial No. 424,999.

To all whom it may concern:

Be it known that JOHN W. BROWN, a citizen of the United States, residing at Columbus, in the county of Franklin and State of Ohio, has invented certain new and useful Improvements in Lamps, of which the following is a specification.

This invention relates to lamps, particularly of the type adaptable for use upon motor vehicles.

The invention itself has for its main object the production of a lamp which may be made at a minimum of expense and at the same time shall be positive in its various actions such as locking the various lamp parts in their properly associated relation.

To this end, it is one object of my invention to provide a plurality of hook engaging members designed for cooperation with a suitable hook structure carried by the lamp body, hook engaging members being carried by the lens ring and being properly located around the interior thereof.

A further object of the invention resides in the combination of a means for locking the lens ring and lamp body together and an auxiliary latch structure for positively holding these parts in their locked relation, this auxiliary latch structure being designed to co-operate with any of the hook engaging members located within the lens ring. By this arrangement, the user or operator need pay no attention to any particular manner or position in which the ring should be mounted upon the body being at all times certain that the auxiliary latch structure will be effective no matter in which position the ring is applied so long as the hook structures are brought into proper engagement with their engaging members.

Still another object of my invention resides in the auxiliary latch structure itself. This is of such form that it may be permanently locked in either an operative or inoperative position. This arrangement has been found to be extremely desirable.

With these objects and others of similar nature in view, the present invention resides in the arrangement and combination of parts hereinafter claimed. The preferred embodiment of my invention is shown in the accompanying sheet of drawings in which similar characters of reference designate corresponding parts and in which,

Figure 1 is a view in partial side elevation

and partial vertical section through a lamp embodying the principles of my invention,

Figure 2 is a section taken on line 2—2 of Figure 1 and looking in the direction of the arrows,

Figure 3 is a broken section represented approximately by line 3—3 of Figure 2, and

Figure 4 is a detached view in perspective of the type of hook engaging member used by me.

In these drawings, the lamp body itself is designated by the reference numeral 1 and is provided with an inwardly projecting annular flange 2 at its open outer end. This flange forms a shelf structure or support upon which the flange or shelf 3 of the reflector 4 is designed to rest. By this arrangement, the reflector is positively located with respect to the position of the lamp bulb and thus maintains proper relation therewith at all times. A lens ring 4' is provided which in itself is of general L shape, the leg 5 being designed and of a size to fit the lamp body while the leg 6 overlies the open end of the lamp body and it is from this leg that the lens 7 is mounted in position.

The means for holding the lamp body, lens ring, and reflector in their properly associated relation takes the form of a plurality of spring hook members 8 located equidistantly about the interior of the lamp body. These hooks are preferably made of spring wire and are secured at one end as shown at 9 by means of a rivet or other suitable form of connection to the underside of the body flange 2. This flange is also cut out at suitable intervals as shown at 10 to permit the spring hooks to pass therethrough. These spring hooks are each given a pair of reverse bends 11 and 12 and are of such form that their free ends 13 bear toward the body flange 2. The reflector flange 3 is cut out at suitable intervals as shown at 14 to permit the application of the reflector 100 to its assembled position as shown in Figure 1 and by a slight twist, the hooked ends 13 of the springs 8 bear against the reflector flange and hold it in firm relation with the body flange 2 when the lens ring is removed.

These same spring hooks are utilized to hold the lens ring in its applied position and to this end, this lens ring is provided with a plurality of hook engaging members of the form shown at 15 in Figure 110

4 equally spaced about its interior. These hook engaging members are short sections bent to a general Z shape as shown and have their legs 16 secured to the leg 5 of the lens 5 ring while their legs 17 are secured to the leg 6 of the lens ring. The intermediate portions 18 lie in the same plane and project inwardly at right angles to the axis of the reflector and body and form the means of 10 abutment of the lens ring against the reflector flange when the parts are properly assembled. A slight twist then causes the hooked ends 13 of the springs 8 to engage these intermediate portions and securely 15 clamp them in position upon the reflector flange. In this manner, all of the lamp parts are held in their proper assembled relation. The angular hook engaging members 15 are of comparatively simple construction and 20 may themselves be made of scrap material. In addition to serving the purpose of engaging the hooks, they also properly lock the lens ring upon the body.

In order to guard against the accidental 25 removal of the lens ring from its proper position upon the lamp body, I have provided an auxiliary latch structure in the form of a spring wire 19 properly secured at one end as shown at 20 to the interior 30 of the lamp body and provided with a shoulder portion 22 at its outer end. This auxiliary latch is so located upon the lamp body with respect to the various spring hooks 8 that when the lens ring is properly placed 35 in position upon the lamp body to be engaged by the hooks, the auxiliary latch 19 will snap into position beyond the shoulder 21 formed by one end of any of the hook engaging members 15. By this arrangement, the user need take no precautions 40 about properly applying the lens ring except that it be in such position to be engaged by any of the spring hooks 8. In other words, this auxiliary spring latch 19 is so positioned that it will engage with any of the 45 hook engaging members 15.

In order to move the auxiliary latch 19 out of engagement with the shoulder 21 to permit removal of the lens ring, I have 50 provided a guard member or plate 23 which is also pivotally mounted at its lower end as shown at 24 to the lamp body. Its upper end is movable over that portion of the lamp body in which the slot 25 is located which 55 permits the projection of the end 21 of the auxiliary latch therethrough. By moving this guard member 23 to the right as shown in Figure 2, this auxiliary latch will be retracted and it may be held positively in 60 such retracted position by tightening of

the nut 26 which is carried by the threaded bolt 27 secured to the guard plate 23. This threaded bolt projects through the slot 28 in the lamp body and the nut 26 may be of such form to also serve as a handle piece 65 in moving the guard plate from one position to another.

It will thus be apparent that the auxiliary latch may be removed from its operative position and it may be held positively in 70 such removed position by tightening of the nut 26 against the lamp body. Likewise, when the guard plate is moved to the position shown in Figure 2, it may be positively held in such position by again tightening 75 the nut. However, I have found it desirable to so proportion the spring 19 to automatically force the guard plate 23 to the position shown in Figures 2 and 3 which will then only necessitate loosening of the nut 26 when 80 it is desired to move it from the right of Figure 2 to the left. This is accomplished by the inclined portion 29 of the auxiliary latch bearing against the guard plate itself.

What I claim is:

1. In a headlight, a lamp body, a reflector therein, means carried by said body to limit the reflector's inward movement, a lens ring, a plurality of hook structures carried by said body, a plurality of individual hook 90 engaging members equally spaced about the interior of said ring including an inwardly projecting part and an angular part adjacent the side portion of said ring, an auxiliary latch structure located and arranged 95 to engage the angular part of any of said members to prevent accidental removal of said ring.

2. In a head light, a lamp body, a reflector therein, means carried by said body to limit the reflector's inward movement, a lens ring, a plurality of hook structures carried by said body, a plurality of individual hook engaging members equally spaced about the interior of said ring including an inwardly 100 projecting part and an angular part adjacent the side portion of said ring, an auxiliary latch structure located and arranged to engage the angular part of any 105 of said members comprising a spring member carried by and passing through a slot in said body and engaging said ring, a guard member pivoted to said body whose free end is movable to lie beneath said spring and body, and means for locking said guard 110 member in either a position to permit or to prevent passage of said spring through said slot.

In testimony whereof I affix my signature.
JOHN W. BROWN.
